UNITED STATES PATENT OFFICE.

HERMANN REICHE, OF MILLSTONE, NEW JERSEY.

PENCIL.

1,106,160.

Specification of Letters Patent.

Patented Aug. 4, 1914.

Application filed June 3, 1910. Serial No. 564,792.

To all whom it may concern:

Be it known that I, HERMANN REICHE, a citizen of the United States, and a resident of Millstone, in the county of Somerset and State of New Jersey, have invented a new and Improved Pencil, of which the following is a full, clear, and exact description.

This invention relates to certain improvements in pencils, and more particularly to 10 that type of pencil in which the marking material is contained within an inner chamber or compartment and fed therefrom as required for use.

My invention relates particularly to the 15 feeding and supporting means for the marking material, and the main objects of my invention are to facilitate the delivery of the material; to sharpen the point of the material or to reduce the cross sectional area 20 thereof as the material is delivered, and to accomplish this reducing or sharpening action by a very simple form of mechanism.

A further important feature of my invention is a storing of the erasing material 25 or abrasive within the same pencil body with the stored marking material and to deliver the erasing material from said body as desired and by means of very simple mechanism.

30 The invention consists in the combination and arrangement of parts hereinafter particularly pointed out in the claims.

Reference is to be had to the accompanying drawings, forming a part of this specification, in which similar characters of reference indicate corresponding parts in all the figures, and in which—

Figure 1 is a side elevation of a pencil constructed in accordance with my invention; 40 Fig. 2 is a longitudinal section therethrough; Fig. 3 is a longitudinal section similar to a portion of Fig. 2, but taken in a plane at right angles to Fig. 2; Fig. 4 is an end view of the cap or tip at the delivery 45 end of the pencil; Fig. 5 is a transverse section on the line 5—5 of Fig. 3; Fig. 6 is a transverse section on the line 6—6 of Fig. 2, but on an enlarged scale; Fig. 7 is a side elevation of the eraser delivering member; Fig. 50 8 is a side elevation of the pencil, the parts of the tip being distorted to sharpen the marking material; and Fig. 9 is an end view of the tip as shown in Fig. 8.

In the specific form of pencil illustrated 55 in the accompanying drawings, I employ

a body portion 10, preferably tubular in form and constructed of any suitable material, as, for instance, aluminum alloy. This tubular body is adapted to contain not only the marking material, but also the erasing 60 material, and at opposite ends of the body are separate devices for individually delivering these materials for use. The erasing material is preferably in the form of a core or rod 11 and is supported within an inner tube or chamber 12, extending lengthwise of the body 10 and concentric therewith. The body 10 at one end, has a neck portion 13 of reduced diameter and the inner tube 12 has a neck portion 14 of slightly enlarged 65 diameter and rigidly secured within the neck 13. This holds the body 10 and the inner tube 12 in their proper relative positions, and prevents movement of one in respect to the other. The tube 12 has an outwardly-extending bead 15 adjacent the inner end of the neck 13, and adjacent this bead the wall of the tube is provided with inwardly-directed threads 16, which will engage with the outer surface of the erasing 70 material and cause a relative longitudinal movement of the tube and erasing material when one is rotated in respect to the other.

For rotating the erasing material, I provide the device shown particularly in Fig. 7. This device comprises a short tube 17 fitting within the neck 14 and having its inner end split to form fingers 18, each of which has an outwardly-extending portion fitting into the bead to prevent relative longitudinal movement of the tube 12 and the feeding member 17. The feeding or delivering member 17 has an outwardly-extending flange 19, preferably milled at its outer edge and disposed adjacent the ends of the neck portions 13 and 14. Beyond this milled flange is a guiding nozzle or holder 20 for the erasing material. Intermediate the ends of the member 17 are two or more inwardly-extending, oppositely-disposed projections or dogs 21, which may be formed by the bending in of a portion of the wall of the member. These projections engage with grooves in the erasing material, so as to prevent relative rotary movement of the material and the member, but they are free to slide lengthwise of the material. By rotating the member 17 in respect to the body 10, the erasing material 11 is rotated with the member and caused to feed through the 110

threads 16 in a direction dependent upon the direction of rotation of the member. Thus the material may be fed out or withdrawn to any extent desired.

At the opposite end of the pencil, there is provided a means for delivering the marking material and for sharpening and compressing the same. As illustrated, the end of the body 10 is subdivided by a series of 10 longitudinally-extending slots, so as to form a series of prongs or fingers 22. These fingers or prongs are elastic, and intermediate their ends they are concave. At the outer end of each finger there is a bead or projection 23, which serves to hold a tip 24 in place. This tip has a substantially cylindrical portion 25 inclosing the prongs or fingers, and a conical portion terminating at its outer smaller end in a guide 26 through 15 which the marking material is delivered. At the intersection of the cylindrical portion 25 and the conical portion, is an annular bead 27, into which the projections 23 extend, so as to prevent longitudinal movement of the tip on the body, but to permit 20 free rotation of one in respect to the other. The tip along the length of the guide 26 and along a portion of the length of the conical portion, is separated into two sections by 25 oppositely-disposed, longitudinally-extending slots 28, the purpose of which will be set forth more fully hereinafter.

Within the tip 24 is a plate 29 serving as a guide for the marking material, and also 30 serving as a propeller for delivering the marking material to the guide. The plate is preferably formed of sheet metal and extends lengthwise of the tip and substantially diametrically thereacross. The plate may 35 have projections 30 for engagement with the slots 28, to prevent the rotation of the plate in respect to the tip. At its rear end, the plate is split into four separate fingers 31, 32, 33 and 34. The two outer of these 40 fingers, 31 and 34, are bent substantially at right angles, and engage with the ends of the prongs or fingers 22 of the body, so as to prevent longitudinal movement of the plate in respect to the body. The two intermediate fingers or prongs 32 and 33, extend lengthwise into the body between the 45 fingers 22, and the ends are bent to form propeller vanes. The vane 32 is somewhat longer than the vane 33, the difference in length and the difference in the angle of 50 inclination of the end, being dependent upon the size and character of the material to be delivered. Along the length of the plate, there are a plurality of transverse slits, and 55 the portions of the plate between these slits are struck up laterally in opposite directions, so as to form a series of opposite grooves or channels 35, 36, 37 and 38. These 60 are all in alinement with each other, and 65 serve to receive the material and guide the

same axially toward the outlet end of the tip 24.

The marking material is preferably of a plastic nature and is supported within the body in the form of a helical coil 70 39 encircling the tube 12 and disposed in the annular chamber between this tube and the wall of the body. As the tip is rotated in one direction in respect to the body, the propeller vane 32 will engage 75 above the first portion of the helix, and will tend to pull the coil lengthwise and guide the material to the series of guiding grooves or loops 35, 36, 37 and 38, which direct the material lengthwise of the device in a 80 straight line toward the outlet guides 26. The several loops or guides 35, 36, 37 and 38 decrease in size from the beginning loop 35 to the terminal loop 38, so that as the material moves along the loops, it is compressed 85 and reduced in cross sectional area, so that a lesser quantity of the material has to be removed in sharpening the point. As the tip is rotated in the reverse direction, the vane 33 engages with the under side of the 90 last coil of the helix and draws the material back.

One important feature of my invention involves the sharpening of the point by the guide 26. This guide, when the parts are 95 in the normal position as indicated in Fig. 4, presents a tubular passage for the marking material, but by reason of the slots 28, the two opposite halves or sections of the guide may be moved laterally in respect to each 100 other, so as to bring one side of one section and the opposite side of the other section, toward the axial line of the pencil, as illustrated in Figs. 8 and 9. These two edges which are brought together, may have their 105 inner edges sharpened or cut at an angle, so that when the parts are in the positions illustrated in Figs. 8 and 9, and the material is rotated within the guide by the rotation of the body in respect to the tip, the material will be sharpened and brought to a point. By releasing the guide, the parts immediately return to the position shown in Fig. 4. The material may be advanced 110 without a sharpening action, by permitting 115 the sections of the guide to remain in normal position, and the material may be advanced or withdrawn by reversing the direction of rotation of the body in respect to the tip. In the sharpening device illustrated, the sections of the sharpening guide 26 are integral with the remainder of the tip and the movement is due to the elasticity of the metal. It is evident that the combined guide and sharpener could be formed 120 separately from the tip of the body and the sections moved laterally in guides rather than being distorted.

In the form illustrated I support the marking material in the form of a helical 125

coil within the body, but it is evident that it might be supported in other ways.

Having thus described my invention, I claim as new and desire to secure by Letters

5 Patent:

10 1. A pencil, having a tubular body; a tubular coil of flexible marking material spirally arranged and disposed in said body; an elongated eraser disposed centrally within said coil; and means for feeding said coil and said eraser from said body.

15 2. A pencil, having a tubular body; a coil of elongated flexible marking material spirally disposed in said body; an elongated eraser disposed within said coil; means for adjustably supporting said eraser in said body and coil; and means for independently feeding said marking material.

20 3. A pencil, having a tubular body; an inner tube open at one end and suspended in said body to provide storage space between said tube and said body; a spirally-coiled flexible marking material disposed in said body and between the inner tube and wall 25 of said body; means for feeding said marking coil from one end of said body, to serve as a marking element for said pencil; an elongated eraser mounted in said inner tube; and means for feeding said eraser from said 30 inner tube.

35 4. A pencil, having a tubular body; an inner tube open at one end and suspended in said body to provide storage space between said tube and said body; a spirally-coiled flexible marking material disposed in said body and between the inner tube and wall of said body; means for feeding said marking coil from one end of said body, to serve as a marking element for said pencil; an elongated eraser mounted in said inner 40 tube; and a screw-threaded section in said tube to engage said eraser to move the same

lengthwise of said tube when revolved therein.

5. A pencil, having a tubular body; an inner tube open at one end and suspended in said body to provide storage space between said tube and said body; a spirally-coiled flexible marking material disposed in said body and between the inner tube and wall of said body; means for feeding said marking coil from one end of said body, to serve as a marking element for said pencil; an elongated eraser mounted in said inner tube; a screw-threaded section in said tube to engage said eraser to move the same lengthwise of said tube when revolved therein; and means engaging said eraser for rotating the same.

6. A pencil, having a tubular body; an inner tube open at one end and suspended in said body to provide storage space between said tube and said body; a spirally-coiled flexible marking material disposed in said body and between the inner tube and wall of said body; means for feeding said marking coil from one end of said body, to serve as a marking element for said pencil; an elongated eraser mounted in said inner tube; a screw-threaded section in said tube to engage said eraser to move the same lengthwise of said tube when revolved therein; and means adjustably mounted on said eraser to slide thereon, said means adapted to hold said eraser to rotate the same in said tube.

In testimony whereof I have signed my name to this specification in the presence of two subscribing witnesses.

HERMANN REICHE.
